DESIGN FOR A JEWELRY CHARM

David Gordon, Los Angeles, Calif.

Application August 13, 1945, Serial No. 121,402

Term of patent 7 years

(Cl. D45—19)

To all whom it may concern:

Be it known that I, David Gordon, citizen of the United States, residing at Los Angeles, in the county of Los Angeles and State of California, have invented a new, original, and ornamental Design for a Jewelry Charm, of which the following is a specification, reference being had to the accompanying drawing, forming part thereof.

All figures are enlarged.

Fig. 1 is a perspective view of a jewelry charm showing my new design;

Fig. 2 is a side elevational view of the jewelry charm;

Fig. 3 is a front elevational view thereof taken in the direction of arrow 3 of Fig. 2;

Fig. 4 is a side elevational view thereof taken in the direction of the arrow 4 of Fig. 3;

Fig. 5 is a rear elevational view of the jewelry charm taken in the direction of the arrow 5 of Fig. 2.

Fig. 6 is a perspective view similar to Fig. 1 with the charm in an open position; and

Fig. 7 is a top plan view of the jewelry charm.

I claim:

The ornamental design for a jewelry charm, substantially as shown and described.

DAVID GORDON.
